GAS PRODUCING APPARATUS

Frank J. Nolan, Bridgeport, Conn., assignor to
Electro-Gas Corporation, Rochester, N. Y.

Application February 23, 1939, Serial No. 257,975

8 Claims. (Cl. 261—99)

This invention relates to gas producing apparatus wherein air is compelled to travel a circuitous passage through a vapor saturated diffusion chamber under constant pressure to produce a dry fixed gas from liquid hydrocarbons, particularly gasoline, in variable volume as required.

One of the objects of this invention is the producing of a dry fixed gas containing all the elements of the liquid hydrocarbon used, within the limits of normal atmospheric temperatures.

A further object of this invention is the production of a dry fixed gas containing all the elements of the liquid hydrocarbon used within a predetermined temperature range without regard to the normal atmospheric temperature or degree of volatility of such liquid hydrocarbon.

Another object of this invention is to provide an apparatus whereby a variable volume of dry fixed gas containing all the elements of the hydrocarbon used, may be produced within the limits of normal atmospheric temperatures, or within a predetermined temperature range to adapt it for use under specific conditions, the pressure to remain constant regardless of volume variation within the capacity of the machine.

Further objects and advantages will be apparent from the following description of the invention as is hereinafter fully disclosed.

In the accompanying drawings:

Figure 1 is a side elevation of the invention, partly in section.

Fig. 2 is a sectional elevation taken on line a—a in Figure 1, showing the arrangement of the wicking in relation to the air distribution system.

Fig. 3 is a perspective view showing an air distributor part, partly in section.

Fig. 4 is a sectional plan view taken on line b—b in Figure 1, showing the wick arrangement and air distribution through the respective parts of the machine.

Fig. 5 is a front elevation of the device showing the centrifugal pump body housing and impeller, with the housing cover removed, and a sectional view of the intake manifold, and

Fig. 6 a cross sectional view in elevation of the centrifugal pump and pivotally disposed clapper valve closure.

The reference characters indicate the same parts in the several drawings.

In the practice of the invention, as shown in Figure 1, the body portion 1 comprises a substantially rectangular sheet metal tank, the bot-

tom of which forms a secondary rectangular tank 1—a for containing a desired liquid hydrocarbon. A longitudinal wall 2 subdivides the interior of the tank into two parts, and the lower edge of the said wall clears the bottom 5 of the secondary tank by a fractional part of an inch to permit the liquid content to rise to a level on both sides thereof, as shown in Fig. 2.

A top or closure portion 3 provides a removable gas tight cover for the tank body portion 1 and may be secured by suitable means. The air diffusion system, as shown in Fig. 4, is disposed within the upper subdivided body portion of the tank body or diffusion chamber, and consists of a series of three tubular air conducting 15 members 4 joined to a common receptacle member 5, said receptacle members for each subdivision being detachably secured on the inside of the body portion opposite to the intake end 29, and the outlet end 31 thereof. 20

A rectangular manifold at the rear end of the body portion, by means of suitable openings therein, connects the longitudinally divided sections of the diffusion chamber. A series of air distributors or diffusion means 9, are mounted 25 on the tubes 4, the apertures 4—a in said air distributors in each series being equivalent to intake and outlet areas in the tank body. A rounded wick supporting member 10 is longitudinally disposed over each series of air distributors 9, and each series of air distributors is staggered so that the apertures therein are not in line with each other. 30

The tube members 4 are so arranged that each series of wick members 11 may extend upward 35 from the diffusion chamber shelf 1—b and occupy the intervening space between said tubes and pass thereover into the lower liquid containing portion 1—a of the tank body to provide a continuous circulation of liquid hydrocarbon. A blanket of woven material 12 of desirable density completely covers the top, 40 sides, and one end of each divisional assembly.

A liquid level float controlled member 14 is mounted adjacent the lower liquid containing 45 portion 1—a of the tank body at the rear end thereof, the liquid hydrocarbon entering the level control member 14 through a pipe 15 from the supply tank, (supply tank not shown) thence through the control member and into the tank portion through the pipe 16. A pressure equalizing pipe 17 connects the manifold in the diffusion chamber with the float chamber in the control member. This liquid level control member is well known in the art and is manufactured 50 55

by the Detroit Lubricator Company of Detroit, Michigan.

A standard fractional horse-power motor 24 is mounted on a suitable base member 24—a secured to the top or closure 3 of the tank body 1. A pressure pump 18 is mounted on the rear end of the motor housing, and its impeller means (not shown) is connected by suitable reduction gears to the motor shaft. On the suction side of the pump a pipe 19 extends into the liquid containing portion of the tank body 1—a. The liquid hydrocarbon drawn up through the pipe 19 is forced through the pipe 20 which is connected with spray nozzles 21 located in each 15 section of the diffusion chamber, and through a nozzle 22 located in the manifold chamber 8. A centrifugal fan 23, of special design which permits definite determination of the pressure generated, by means of centrifugal clearance in 20 one direction, and lateral clearance on either side of the impeller within the fan housing. The impeller 23—a is mounted on the motor shaft, the fan housing being mounted on the motor housing. The outlet opening of the assembled fan is held in a normal closed position by a balanced clapper valve pivotally suspended in the outlet opening as shown in Fig. 6.

A turbulence silencing chamber 26 is operatively mounted above the intake opening 27 in 30 the fan housing cover 28, and communicates therewith. Under ordinary conditions, when air is used at normal atmospheric temperature, a closure is provided for the turbulence chamber (closure not shown). Under conditions where it may be desirable to preheat the air taken in by the fan, a thermostatically controlled heating unit may be inserted in said chamber 26 which incidentally serves as a closure therefor.

40 The fan assembly is connected to the intake side 29 of the diffusion chamber portion of the tank body by a manifold 30 which is bolted to the tank body as shown in Fig. 5. The outlet side 31 of the diffusion chamber is provided with 45 a balanced clapper valve closure 32 which is pivotally suspended in the outlet manifold housing 31—a, and remains in a normal closed position by gravity on a seat which is machined at an angle of approximately ten degrees to insure complete closure. Both intake and outlet clapper valves are balanced so that the slightest flow of gas from the outlet opening through a burner (burner not shown) will cause simultaneous opening of said valves; and closing the gas cock 55 to such burner causes said valves to return to a normal seated position, the gas within the body portion or diffusion chamber remaining static and ready for use.

Complete saturation of the air introduced to 60 the wick assembly in the diffusion chamber is ensured by the perpetual circulation of the liquid hydrocarbon by means of a multiplicity of bleached loosely twisted or roved cotton yarn wicks 11, one end of which reach into the bottom 65 of the fluid containing portion of the tank body 1—a, and by capillary attraction raise the liquid over the wick supporting members 10, and by precipitation at the other end deposit the un- 70 volatilized portion of such hydrocarbon on the shelf member 1—b where the liquid returns to the lower tank portion 1—a. The circulation of the hydrocarbon is continuous as long as the liquid remains in the container, and is not dependent upon other than the natural laws gov-

erning capillary attraction in one direction, and precipitation in the other for its continuation.

A sub-tank 1—c, separate from and adjacent to the under face of the fluid containing portion 1—a of the tank body 1 is provided so that 5 when it may be found desirable to maintain the temperature most suitable to volatilization of the fluid hydrocarbon being used, a heat conducting medium such as oil may be used in the sub-tank, and a thermostatically controlled heating unit 10 33 provided therefor.

The air diffusing system is not limited to the type disclosed in the drawings. It may be varied as to form to maintain an equivalent distribution of air. The time element is a critical in 15 the art of making this type of fixed dry gas, the elapsed time between the entrance of outside air into the diffusion chamber, its absorption of hydrocarbon fractions to a point of saturation without precipitation, and emergence as a dry 20 fixed gas is definitely controlled by the areas in the air diffusing means and the intake and outlet areas in the diffusion chamber. The foregoing statement is predicated upon the discovery that, in an apparatus of the character described, where 25 both intake and outlet areas are 1.76 square inches, employing an air pressure constant of 3½ ounces (water pressure) and a maximum output of 12 cubic feet per hour, there is produced a logy or heavy dry fixed gas of maximum 30 B. t. u. content within the limits of the type of liquid hydrocarbon used therein, and which, when gasoline is employed exceeds 500 B. t. u. per cubic foot.

The operation of the apparatus is as follows: 35 The constant speed motor 24 driving the centrifugal fan, propels a current of air of definite pressure through the clapper valve 25 on the intake side of the diffusion chamber into the receptacle member 5 from which it is diffused 40 through the several tube members 4 and through the apertures 4—a in the air distributors 9 mounted on said tubes. The diffused air takes up the hydrocarbon fractions from the surrounding wicking system, said wicking system in addition to capillary attraction and precipitation of the hydrocarbon is assisted by the spraying means 21 to become completely saturated. The gas vapor continues to flow through the hydrocarbon sprayed interior of the diffusing chamber 45 through the manifold 8 from where it continues 50 through a second air diffusing chamber and sprayed wicking system to the outlet side 31 which is connected to the distribution system 55 for use. The static reserve within the diffusion chamber permits instantaneous use of the gas when the centrifugal fan motor is started. There is no production of gas until a burner is opened 60 in the distribution line, and a variable volume of dry fixed gas is delivered for consumption at 65 a constant pressure within the capacity of the machine.

What is claimed as the invention and desired to be secured by Letters Patent, is:

1. In an apparatus for producing a dry fixed 65 gas from liquid hydrocarbons, a body portion having a diffusion chamber and a lower liquid hydrocarbon container, a wick supporting air diffusing means disposed in the diffusion chamber, a multiplicity of roved yarn wicks of unequal pen- 70 dence disposed between and over the air diffusing means and extending into the lower liquid hydrocarbon container to provide a continuous circulation of liquid hydrocarbon through the diffusion chamber, and an air impelling means to force a current of air through the carburet- 75

ting means and wick assembly at a predetermined pressure and in variable volume.

2. In an apparatus for producing a dry fixed gas from liquid hydrocarbons, a longitudinally bisected body portion having two diffusion chambers connected by a manifold, the lower part of said body portion forming a communicating hydrocarbon container, balanced automatic closure members pivotally disposed in the inlet and outlet opening in the diffusion chambers of the body portion, a wick supporting air diffusing means disposed in said diffusion chambers, a multiplicity of roved yarn wicks disposed between and over the carburetting means, said wicks being of unequal pendance, one end extending into the lower liquid hydrocarbon container to provide a continuous circulation of hydrocarbons, and an air impelling means to force a current of air through the carburetting means and wick assembly at a predetermined pressure and in variable volume.

3. In an apparatus for producing a dry fixed gas from liquid hydrocarbons, a longitudinally bisected body portion having two diffusion chambers connected by a manifold, the lower part of said body portion forming a communicating hydrocarbon container, balanced closure members pivotally disposed in the intake and outlet opening in the diffusion chambers of the body portion, a wick supporting air diffusing means disposed in said diffusion chambers, a multiplicity of roved yarn wicks disposed between and over the air diffusing means, said wicks being of unequal pendance, one end extending into the lower liquid hydrocarbon container to provide a continuous circulation of hydrocarbon, a hydrocarbon spraying means disposed in the diffusion chambers and manifold therebetween, and an air impelling means to force a current of air through the carburetting means and wick assembly at a predetermined pressure and in variable volume.

4. Same as claim 3, and means for heating the liquid hydrocarbon to a predetermined temperature.

5. In an apparatus for producing a dry fixed gas from liquid hydrocarbons, a body portion having a circuitous passageway through the diffusion chamber therein, the lower part of said body portion forming a receptacle for liquid hydrocarbons, a wick supporting air diffusing means disposed in the diffusion chamber, a multiplicity of roved yarn wicks of unequal length or pendance disposed between and over the air diffusion means, the longer end of said wicks

extending into the liquid hydrocarbon receptacle to provide a continuous circulation of liquid hydrocarbons, and an air impelling means to force a current of air through the diffusing means and wick assembly at a predetermined pressure and in variable volume.

6. In an apparatus for producing a dry fixed gas from liquid hydrocarbons, a body portion subdivided into several diffusion chambers connected by suitable manifold, the lower part of said body portion forming a receptacle for liquid hydrocarbons, a wick supporting air diffusing means disposed in the several diffusion chambers, a multiplicity of roved yarn wicks of unequal pendance disposed between and over the carburetting means, the longer end of said wicks extending into the liquid hydrocarbon receptacle to provide a continuous circulation of hydrocarbons, balanced automatic closure members pivotally suspended in the intake and outlet openings in the diffusion chambers of the body portion, and an air impelling means to force air through the carburetting means and wick assembly at a predetermined pressure and in variable volume.

7. In an apparatus for producing a dry fixed gas from liquid hydrocarbons, a longitudinally bisected body portion forming two diffusion chambers connected by a manifold, the lower part of said body portion forming a common hydrocarbon receptacle, balanced automatic closure members pivotally disposed in the intake and outlet openings in the diffusion chambers of the body portion, a wick supporting air diffusing means disposed in said diffusion chambers, a multiplicity of roved yarn wicks disposed between and over the carburetting means, said wicks being of unequal pendance, the long ends thereof extending into the liquid hydrocarbon receptacle to provide a continuous circulation of liquid hydrocarbons in the diffusion chambers, a hydrocarbon spraying means disposed in the diffusion chambers and connecting manifold therebetween, an air impelling means, means for pre-heating air disposed within the air impelling means, said air impelling means to be capable of forcing air through the air diffusing means and wick assembly at a predetermined pressure and in variable volume.

8. Same as claim 7, and means for heating the liquid hydrocarbon to a predetermined temperature.

FRANK J. NOLAN.
